E. W. Vacher, Inventor

UNITED STATES PATENT OFFICE.

ERNEST W. VACHER, OF ROSELAND, LOUISIANA, ASSIGNOR OF ONE-HALF
TO HENRY FISHER, OF ALBANY, OHIO.

FUNNEL.

SPECIFICATION forming part of Letters Patent No. 633,628, dated September 26, 1899.

Application filed June 15, 1899. Serial No. 720,655. (No model.)

To all whom it may concern:

Be it known that I, ERNEST W. VACHER, a citizen of the United States, residing at Rose-
land, in the parish of Tangipahoa and State
5 of Louisiana, have invented a new and useful
Funnel, of which the following is a specification.

This invention relates to means for filling
lamps, jugs, and other vessels in which the
10 filling up thereof cannot be readily seen, and
has for its object to combine a siphon with a
funnel in such a manner as to indicate when
the vessel is nearly filled and to prevent spilling
by an overflow of the contents thereof.

15 To these ends the present invention consists in the combination and arrangement of parts, as will be hereinafter more fully described, shown in the accompanying drawings, and particularly pointed out in the ap-
20 pended claims, it being understood that changes in the form, proportion, size, and minor details of construction may be made within the scope of the appended claims without departing from the spirit or sacrificing
25 any of the advantages of the present invention.

In the drawings, Figure 1 is a side elevation of the reservoir of a lamp, having the im-
30 proved funnel applied thereto. Fig. 2 is a longitudinal sectional view thereof. Figs. 3 and 4 are modified forms of the invention. Fig. 5 is a detail elevation showing an indicator attachment for the funnel.

Corresponding parts in the several figures
35 of the drawings are designated by like characters of reference.

Referring to the accompanying drawings, 1 designates a funnel of common form having the lower end closed, as at 2, and provided with
40 a transverse opening 3, formed through one side and at or near the closed bottom thereof. Fitted to the outer side of the funnel and communicating with the opening 3 is a tube 4, which is closed at its lower end by an ex-
45 tension 5 of the bottom of the funnel. By reference to Fig. 2 it will be seen that the funnel forms one side of the tube 4. This tube extends upwardly alongside of the funnel for a suitable distance and is provided at
50 its upper end with an outwardly-extending

horizontal branch 6, and inclined down-
wardly and outwardly from the outer end of the branch tube 6 is a pendent tube 7, hav-
ing its lower discharge end 8 located below
the plane of the bottom of the funnel or the 55
inlet of the tube 4, whereby the tubes 4, 6,
and 7 are adapted to form a siphon for empty-
ing the funnel. It is preferable, although
not essential, to have the lower end of the
discharge-tube 7 located below the bottom of 60
the funnel or the inlet-tube 4, and said dis-
charge-tube may be arranged vertically, as
shown in dotted lines in Fig. 2, instead of
being inclined outwardly, as hereinbefore de-
scribed. A suitable ring 14 is provided near 65
the upper edge of the funnel, whereby the
latter may be conveniently hung up.

In the operation of the device, as best shown in Fig. 2, the discharge-leg 7 of the siphon is introduced into the filling-opening 9 of the 70 reservoir of the lamp 10, so that the horizontal branch pipe 6 rests across one side of the upper edge of the filling-opening 9, as at 11, and the leg 7 engages against the opposite inner wall thereof, as at 12, whereby the funnel is held in place and does not require to be supported by the hand of the operator. At the points where the discharge-tube 7 and the transverse tube 6 engage the walls of the 75 opening 9 said tubes are provided with suit-
able serrations or corrugations 15, so that a positive and efficient engagement may be had between the tubes and the walls of the open-
ing. The oil with which the lamp is to be filled
is poured into the funnel, and as the level 80
thereof rises in the funnel the oil will pass
upwardly through the leg 4 to the transverse
branch 6 and thence through the discharge-
leg 7 into the interior of the lamp. When
the lower end 8 of the leg 7 has become sub- 85
merged by the oil in the lamp, the flow of the
oil from the funnel to the lamp will be checked,
and the oil will then flow slowly, thereby in-
dicating that the lamp is nearly filled. After
the flow of the oil has thus been checked the 90
supply of oil to the funnel is stopped and the
level of the oil therein is permitted to fall be-
low the horizontal branch tube 6, so that no
more oil can pass into the lamp and overflow
of the oil is prevented. The funnel may be re- 95
100

moved from the lamp after the oil has stopped running without spilling the latter.

The modification illustrated in Fig. 3 shows the siphon-tube 20 connected to the funnel 5 at one end only and not extending upward against the funnel, while in Fig. 4 has been illustrated a flexible tube 21 to facilitate the filling of jugs. In this latter form the funnel has no means of support and must be held by 10 the hand of the operator.

It will be noted that in all forms but that shown in Fig. 4 the bottom of the funnel is located below the highest portion of the siphon-tube and also below the filling-opening 15 of the vessel, whereby the funnel cannot become entirely emptied, and thereby the vessel cannot be filled to overflowing. Furthermore, the highest portion of the tube is also located intermediate of the top and bottom 20 of the funnel, so that the liquid may flow from the funnel through the siphon-tube.

In Fig. 4 the funnel has been shown with a flexible tube forming the siphon member, and as that portion of the tube which is connected with the funnel will naturally extend downwardly therefrom it is not necessary that the bottom of the funnel be located below the filling-opening of the vessel so long as the lower bend of the tube is located below said 30 filling-opening.

The indicating device for determining when the vessel is nearly filled is clearly shown in Fig. 5 of the drawings, and comprises a float 16, having a central stem 17 35 passing loosely through aligned openings 18 and 19, respectively, formed through opposite sides of the discharge-tube 7, the float being located in vertical alignment with the open lower end of said discharge-tube. It will be 40 understood that the float 16 will rest upon the surface of the liquid contained within the vessel being filled, and as the surface of the liquid rises the float will also rise therewith, so that the projecting portion of the stem 17 45 will gradually indicate the level of the liquid contained within the vessel. Also the float is

adapted to rise against the lower end of the tube 7 and close the same, as indicated in dotted lines, thereby automatically cutting off the supply of liquid and effectually preventing an overfilling of the vessel. 50

Having thus fully described my invention, what I claim as new, and desire to secure by Letters Patent, is—

1. In a device of the class described, the 55 combination with a funnel, of a siphon-tube having the highest portion thereof located intermediate of the top and bottom of the funnel, substantially as shown and described.

2. In a device of the class described, the 60 combination with a funnel, of a rigid tube communicating at its lower end with the interior of the funnel and extending upwardly and terminating short of the top of the funnel, a transverse tube in communication with 65 the upper end of the upwardly-extending tube, and an outwardly-inclined tube pendent from the outer end of the transverse tube, substantially as shown and described.

3. In a device of the class described, the 70 combination with a funnel having a closed bottom, an extension thereof projecting at one side of the funnel, and a transverse opening provided through the latter side and immediately above the projecting extension, of 75 an upwardly-extending tube connected exteriorly to the funnel communicating laterally through the opening therein and closed at its lower end by the bottom extension of the funnel, a transverse tube communicating 80 with the upwardly-extending tube, and an outwardly-inclined tube pendent from the outer end of the transverse tube, substantially as shown and described.

In testimony that I claim the foregoing as 85 my own I have hereto affixed my signature in the presence of two witnesses.

ERNEST W. VACHER.
